UNITED STATES PATENT OFFICE.

OBED C. BILLMAN, OF CLEVELAND, OHIO.

CAR-COUPING.

1,151,559.

Specification of Letters Patent. Patented Aug. 31, 1915.

Application filed January 22, 1909. Serial No. 473,702.

To all whom it may concern:

Be it known that I, OBED C. BILLMAN, a citizen of the United States, residing at Cleveland, in the county of Cuyahoga and State of Ohio, have invented certain new and useful Improvements in Car-Couplings, of which the following is a specification.

My invention relates to car couplers and more particularly to that class known as the "vertical plane" or "M. C. B." type, and the paramount object of the invention is to provide a generally-improved device of this class which will be exceedingly simple in construction, cheap of manufacture, and efficient in use, and which, by reason of perfection in details to meet the various demands of actual service, will be better adapted to its intended purposes than any other device of the same class, with which I am 20 acquainted.

The perfection in details above referred to or the subsidiary objects of the invention may be stated as follows:

First: An object of the invention is to 25 provide a simple and efficient knuckle opening and holding means for automatically moving the knuckle to and holding the same in its open position when released by the locking device.

Second: A further object is to provide a generally-improved "lock-set" for the locking device the functions and objects being, as the name implies, to enable the trainman to "set the lock" in one of two connected couplers so that without further attention the knuckle will be permitted to swing open in the act of cutting a train as in switching or the like, and, at the same time, the parts will automatically assume their proper position preparatory to effecting an automatic coupling when again brought into contact with an opposing coupler.

Third: A still further object is to provide a locking device adapted to automatically release the tail of the knuckle should the draw-head be broken from the draw-bar, or the latter become torn from its carriage fastenings while the train is in motion, thereby preventing the draw-head, or the entire coupler, as the case may be, from being withdrawn to drop upon the roadway and displace or wreck cars, as sometimes occurs in actual service when couplers not having this feature of construction are in use.

With the above mentioned ends in view,

the invention in its present embodiment consists in the novel construction, arrangement, and combination of parts, hereinafter described, illustrated in the accompanying drawings, and particularly pointed out in 60 the appended claims.

Referring to the accompanying drawings, forming part of this specification, Figure 1, is a perspective view of a car-coupler, embodying my invention, the parts being shown 65 in locked position. Fig. 2, a horizontal sectional view of two connected couplers, the locking device of one being shown in "lock set" position. Fig. 3, a similar view of one of the couplers showing the parts in opened 70 or unlocked position, the knuckle being in its open position preparatory to effecting an automatic coupling.

Similar numerals of reference designate like parts throughout all the figures of the 75 drawings.

Upon reference to the drawings, it will be seen that the improved coupler consists of a draw-head 1, provided with an ordinary draw-bar 2, designed to be connected to a car 80 in the ordinary manner, and having pivoted to it a knuckle 3, which is provided with an arm 4, arranged to swing in a horizontal recess or cavity 5, of the draw-head.

The knuckle is locked in its connected or 85 closed position by means of a combined locking-dog and "knuckle-opener" 6, horizontally arranged and pivotally-mounted within the recess or cavity 5, by means of a vertically-arranged pivot-pin 7, passing through 90 the upper and lower walls of the draw-head.

The locking-dog and "knuckle-opener" consists of a main body portion or arm having at its front a convex face 8, and a 95 notch or shoulder 9, adapted to take over and engage the tip or tail of the arm 4, of the knuckle 3, when the latter is moved to its connected or closed position, as shown most clearly in Figs. 1, and 2, of the 100 drawings.

In order to provide means for releasing the arm 4, of the knuckle 3, and "opening" the latter, a chain 10, is secured to the rear of the main body portion or arm of the 105 locking-dog and "knuckle-opener" 6, and a spring-arm 11, suitably secured to or formed integral with the locking-dog, is adapted to engage a pivotally-mounted lock-set pawl or lever 12, hereinafter described, 110

carried by the arm of the knuckle, and to have its free end depressed against the lock-set pawl 12, when the locking-dog is moved rearwardly, whereby, when the tip of the 5 arm of the knuckle has been released from engagement with the shoulder 9, the knuckle will be thrown to and maintained in its open position as shown most clearly in Fig. 3, of the drawings.

- 10 The chain 10, passes out through an opening 13, in the rear wall of the coupler-head and is secured to a suitable operating means secured to the end of the car, and should the draw-head be broken from the draw-bar, 15 or the latter become torn from its fastenings for securing the same to a car, while the train is in motion, the chain 10, will move the locking-dog to its unlocked position, thus automatically releasing the tail of the 20 knuckle, releasing the adjacent car, and thereby preventing the draw-head, or the entire coupler, as the case may be, from being withdrawn to drop upon the roadway and thus displace or wreck cars, as often 25 occurs with couplers not having this feature of construction.

When the knuckle is moved to its closed position, in the act of coupling, by its engagement with an opposing coupler, the tail 30 or tip of the arm of the knuckle will engage with convex face 8, of the locking-dog, thus depressing the spring-arm 11, against the lock-set pawl 12, arranged in the back of the arm of the coupler until the tip of the 35 arm reaches the shoulder 9, of the locking-dog, when the latter will snap into engagement therewith and be securely held in its closed or locked position until released, as hereinbefore set forth.

40 It will be seen that the spring-arm 11, is not depressed to any great extent except in the opening and closing movements of the knuckle, and locking-dog and "knuckle-opener," so that while in both the coupled 45 and uncoupled position of the parts the spring-arm is largely relieved from tension or compression.

The "lock-set" feature of the invention, 50 in the present instance, comprises a lock-set shoulder 14, so positioned relative to the knuckle-engaging shoulder 9, of the locking-dog that when the latter has been moved beyond its knuckle-releasing position, the shoulder will register with the tip or inner 55 end 12^a, of the pivotally-mounted lock-set pawl or member 12, and the knuckle being in engagement with an opposing coupler it is evident that the pressure of the spring-arm 11, on the head 12^b, will cause the tip 60 or end 12^a, to be moved outwardly and snap into engagement with the lock-set shoulder 14, when the locking-dog is moved as above mentioned substantially as shown in one of the connected couplers of Fig. 2, of the 65 drawings. On the opening of the knuckle

as the cars part the movement of the arm or tail of the knuckle carries the tip 12^a, of the lock-set pawl off of the lock-set shoulder 14, the clearance of the tip 12^a, with respect to the shoulder 14, taking place after the 70 clearance of the arm or tail of the knuckle with respect to the knuckle-engaging shoulder 9. Consequently, the convex face 8, of the locking-dog as the latter closes will come into engagement with the tip 12^a, and allow 75 the knuckle to assume its open position while the locking-dog by the action of the spring-arm 11, assumes its normal or closed position preparatory to effecting an automatic 80 coupling.

From the foregoing description, taken in connection with the accompanying drawings, the operation and advantages of my invention will be readily understood.

Having thus described an embodiment of 85 my invention, I declare that what I claim and desire to secure by Letters Patent, is—

1. In a car coupling, a locking-dog having a lock-set shoulder and a horizontally movable knuckle opening arm, and a knuckle 90 having a lock-set portion adapted, while the knuckle is closed, to engage with said lock-set shoulder when the locking-dog has been moved to its lock set position.

2. In a car coupling, a locking-dog and 95 knuckle-opener having a lock-set shoulder and comprising a knuckle engaging arm and a knuckle opening spring-arm, and a knuckle having a lock-set member adapted to engage with said lock-set shoulder when 100 said locking-dog has been moved to its knuckle releasing position.

3. In a car coupling, a knuckle, a pivoted lock-set member, a knuckle locking member having a lock-set shoulder in co-operative 105 relation to said lock-set member, and a spring carried by said knuckle locking member and extending to and adapted to be compressed against said lock-set member as said knuckle locking member is moved to its 110 knuckle releasing position.

4. A car coupling, comprising a draw-head, a pivoted knuckle provided with an arm carrying a lock-set pawl, and a locking-dog having a shoulder adapted to engage 115 the arm of the knuckle when in its closed position and a spring-arm adapted to engage said lock-set pawl and open the knuckle when said locking-dog is moved to its unlocked position, said locking-dog being provided with a lock-set shoulder adapted to be engaged by said lock-set pawl when the knuckle is held in its closed position and said locking-dog has been moved to unlocked 120 position.

5. In a car coupling, the combination with 125 a knuckle having an arm carrying a lock-set pawl; of a locking-dog normally engaging said arm and provided with a lock-set shoulder and a spring-arm adapted to actu-

ate said lock-set pawl and move the same into engagement with said lock-set shoulder of the locking-dog when the latter is moved to its unlocked position whereby the same 5 is held in lock-set position while the knuckle is held in its closed position.

6. A car coupling, comprising a draw-head, a pivoted knuckle provided with an arm carrying a lock-set member, a locking-dog adapted to engage the arm of the knuckle when in its closed position, and a spring member adapted to engage said lock-set member and open the knuckle when said locking-dog is moved to its unlocked position, 10 said locking-dog being provided with a lock-set shoulder adapted to be engaged by said lock set member when the knuckle is held in its closed position and said locking-dog has been moved to unlocked position.

7. In a car coupling, the combination with a knuckle having an arm carrying a lock-set member; of a locking-dog normally engaging said arm and provided with a lock-set shoulder, and a knuckle opening member 25 adapted to move said lock-set member into engagement with said lock-set shoulder when the locking-dog is moved to an unlocked position whereby said locking-dog is held in lock-set position while the knuckle 30 is in its closed position.

8. In a car coupling, a horizontally movable locking-dog and knuckle opener having a lock-set shoulder, and a knuckle having a lock-set portion adapted to engage with 35 said lock-set shoulder when said locking-

dog has been moved to its knuckle releasing position.

9. In a car coupling, a locking-dog and knuckle opener provided with a lock-set shoulder, and a knuckle having a lock-set 40 member adapted to be engaged by said knuckle opener and to be projected into engagement with said lock-set shoulder when said locking-dog has been moved to its knuckle releasing position. 45

10. In a car coupling, a knuckle having an arm, a lock-set member carried by the latter, a knuckle arm engaging member, and a spring extending between the latter and said lock-set member and adapted to be compressed against said lock-set member as said knuckle arm engaging member is being moved to released position.

11. In a car coupling, a pivotally mounted knuckle arm, a movable lock-set member, 55 and locking dog and knuckle opening members normally positioned, respectively, on opposite sides of said knuckle arm when the latter is closed, said knuckle opening member having a yielding bearing on and being 60 adapted to be placed under tension against said lock set member as said knuckle arm is released by the movement of said locking dog member.

In testimony whereof I have affixed my 65 signature, in presence of two witnesses.

OBED C. BILLMAN.
